FIG.1

FIG.2

FIG.3

FIG.4

FIGURE 1 is a front elevational view of a collapsible bag for liquids, showing our new design;

FIGURE 2 is a side elevational view thereof;

FIGURE 3 is a developed top plan view of the portion shown in full lines; and

FIGURE 4 is an end elevational view of FIGURE 3.

This design patent application is a continuation-in-part of design patent application Serial No. D. 71,017, filed July 23, 1962, now abandoned.

The dominant features of our design reside in the portions shown in solid lines.

We claim:

The ornamental design of a collapsible bag for liquids, substantially as shown and described.
